UNITED STATES PATENT OFFICE

KURT SCHROEDER, OF DORTMUND, GERMANY

SYMMETRICAL PILING MADE OF CHANNEL-IRON SECTIONS

Application filed June 24, 1930, Serial No. 463,415, and in Germany June 24, 1929.

Coffer dams or pilings consisting of channel-iron sections are well known. The channel sections, however, have not heretofore had their interlocking edges shaped symmetrical-
ly with reference to a common medial plane
of the inter-connected walls. Besides, the
locks used as connections between the several
sections have heretofore generally not been
of a double locking character. The present
invention removes these drawbacks by giving
to all the assembled pile sections the same
dimensions and shape of cross section, and
by shaping the inter-engaging locks or joints
between the pile sections so as to be substan-
tially symmetrical with reference to broken
lines $x-x$ which represent medial planes com-
mon to each pair of interlocked wall portions.

The best form of apparatus, at present
known to me, embodying my invention, is
shown in the accompanying sheet of draw-
ings, in which:

Fig. 1 is a plan view of a portion of a
piling assembly, and

Fig. 2 is a detail, horizontal section
through one of the joints shown on an en-
larged scale.

Throughout the drawings like reference
characters indicate like parts.

S, S, represent channel-iron sections, the
adjacent walls W, W, of which are inter-con-
nected, each pair of such connected walls and
the joint or lock uniting them, generally rep-
resented by a , having one and the same medial
plane, represented by a broken line $x-x$.
This joint or lock a , as shown by Figs. 1 and
2, consists of a pair of claws, one wing or
jaw of each of which ends in a hooklike pro-
jection c , whereas the second wing or jaw d
projects straight out and cooperates with an
oppositely disposed shoulder e on the co-
operating pile section edge. Hooks or claws
 c on each abutting wall edge are of corre-
sponding form and shape, each nesting in a
groove b in the adjoining section so that a
symmetrical double locking joint or lock is
obtained, each hook c of one pile section nest-
ing in a groove b under the hook of the other
pile section.

Among the advantages of the described
construction may be noted the elimination of

any tendency to twist apart when the joints
are subjected to tension strains, as these can
be exerted only along the line of the common
medial plane of the joint and of its adjacent
wall sections, and the resisting forces then
developed between the interlocked hooks will
be evenly distributed on either side of that
line of tension. Also, as all the interlocking
surfaces subjected to pressure extend either
at right angles to that line of strain, or
parallel thereto, there will be no resultant
wedging action. Finally, when the joint is
subjected to bending strains, the surfaces e
closely abutting at the ends of the second
wings or jaws d will firmly resist any turning
moment about the axis of the joint, generated
by such bending forces.

The general medial plane of the entire
piling assembly is indicated by the broken
line $y-y$.

Having described my invention, I claim:

1. A system of sheet piling comprising,
in combination, a plurality of channel sec-
tions all having a substantially uniform cross
section so as to be interchangeable, and adapt-
ed to be interconnected with their adjacent
wall portions lying in common planes ex-
tending substantially at right angles to the
general plane of the assembled piling, and
each section edge being provided with a
groove interlocking with a hook-shaped pro-
jection on any adjacent section, said inter-
locking hooks and grooves being arranged
symmetrically with reference to the com-
mon medial plane of each pair of abutting
section walls; whereby said interlocking wall
sections will have no tendency to twist apart
when their joints are subjected to tension
strains exerted along lines lying in said me-
dial plane.

2. A combination such as defined in claim
1 in which said adjacent wall edges also have
abutting surfaces located on either side of
said common medial plane and of said inter-
locking grooved and hook-shaped portions;
whereby additional resistance is afforded to
any turning moment exerted about the axis
of said interlocked joint.

3. A system of sheet piling comprising, in
combination, a plurality of pile sections the

adjacent portions of which lie in substantially one and the same plane and are provided with interlocking hooked portions located in said plane, and with abutting surfaces disposed on either side of said interlocked hooks, said abutting surfaces extending substantially at right angles to said plane.

KURT SCHROEDER.
